UNITED STATES PATENT OFFICE

172,021

DOOR CHIME HOUSING

Alexis C. Grohsgal, Cranston, R. I., assignor to
Cable Electric Products, Inc., Providence, R. I.

Application November 10, 1953, Serial No. 27,532

Term of patent 14 years

(Cl. D72—1)

To all whom it may concern:

Be it known that I, Alexis C. Grohsgal, a citizen of the United States of America, residing at Cranston, in the county of Providence and State of Rhode Island, have invented a new, original, and ornamental Design for a Door Chime Housing, of which the following is a specification, reference being had to the accompanying drawing, forming a part thereof.

Figure 1 is a front elevational view of a door chime housing, showing my new design.

Fig. 2 is a side elevational view.

Fig. 3 is a rear elevational view.

Fig. 4 is a plan view.

Fig. 5 is a bottom view.

I claim:

The ornamental design for a door chime housing, as shown.
